United States Patent Office

Des. 224,882
Patented Oct. 3, 1972

224,882

COMBINED BOTTLE AND DISPENSING PUMP THEREFOR

Marvin Alpern, Glen Ridge, N.J., assignor to
Sterling Drug Inc., New York, N.Y.

Filed Feb. 1, 1971, Ser. No. 111,806

Term of patent 14 years

Int. Cl. D9—01

U.S. Cl. D9—67

FIG. 1

FIG. 2

FIG. 3FIG. 4FIG. 5

FIG. 1 is a perspective view of a combined bottle and dispensing pump therefor showing my new design;

FIG. 2 is a view in side elevation thereof;

FIG. 3 is a view in front elevation;

FIG. 4 is a top plan view, and

FIG. 5 is a bottom plan view.

The opposite side from FIG. 2 is a mirror image thereof.

I claim:

The ornamental design for a combined bottle and dispensing pump therefor, as shown and described.
